UNITED STATES PATENT OFFICE.

WALTER V. REID, OF RICHMOND, INDIANA, ASSIGNOR TO PETTIS A. REID, OF RICHMOND, INDIANA.

FEED MECHANISM FOR WIRE-FENCE MACHINES.

1,242,594.

Specification of Letters Patent.

Patented Oct. 9, 1917.

Application filed January 31, 1916. Serial No. 75,364.

To all whom it may concern:

Be it known that I, WALTER V. REID, a citizen of the United States, residing at Richmond, in the county of Wayne and State of Indiana, have invented certain new and useful Improvements in Feed Mechanism for Wire-Fence Machines; and I do hereby declare the following to be a full, clear, and exact description of the invention, such as will enable others skilled in the art to which it appertains to make and use the same.

This invention relates to mechanism for feeding material of desired lengths, longitudinally, to machines adapted to receive material in such manner, and more particularly to that class of machines used for making wire fence, wherein the stay wire is fed to the machine automatically from the coil of wire into position to be operated upon by suitable devices adapted to form loops in the stay and wrap the loops around the strand wires.

The objects of the invention are to provide a feed mechanism of the character referred to whereby the material or wire for forming a stay or the like may be fed to the machine automatically from the coil of wire, longitudinally or endwise, in desired lengths to form either a single stay at a time, or two stays or stay lengths at a time, either of equal length or of different lengths, or stays of different lengths, alternately, by feeding first a long stay or stay length, and then a short stay or stay length, or vice versa; such mechanism being so constructed that by varying the number of feed rolls used and making the required alterations in the shape of the cam for elevating or shifting said rolls and the cam for engaging the feeding faces of the rolls with the material to be fed, and also varying the ratio of the cam shaft and feed roll shafts to the main driving shaft, a number of equal lengths or unequal lengths of material can be fed alternately or simultaneously, and the time required to do such feeding, in a cycle of a machine to which the material is being fed, can be varied to suit the requirements of such machine.

The invention will first be hereinafter more particularly described, with reference to the accompanying drawings, which are to be taken as a part of this specification, and

then pointed out in the claims at the end of 55 the description.

Referring to said drawings, which illustrate a mechanism to feed one length during an operation of one cycle, and a different length during the next cycle of movement; 60

Figure 1 is a front elevation of a preferred form of feeding mechanism embodying my invention;

Fig. 2 is an end elevation of the same;

Fig. 3 is a top plan view thereof;

Fig. 4 is a sectional plan, taken on the line 4—4 of Fig. 1;

Fig. 5 represents a partial sectional elevation with the shifting feed rolls at their lowest position and with the co-acting tilting feed roll thrown back into position not to engage the material to be fed;

Fig. 6 is a detail view of the cam for elevating the shifting rolls;

Fig. 7 is a detail view of the cam for 75 throwing the tilting feed roll out of engagement with the shifting rolls or into inactive position; and

Fig. 8 is a detail of the shifting feed rolls, on a slightly enlarged scale, so as to more 80 clearly illustrate their construction.

Referring to said drawings, in which the same reference letters or numerals are used to denote corresponding parts in different views, the letter A may denote the frame in 85 which the operative parts of the feed mechanism are journaled, and B the power shaft of the machine, which, when revolved at the same speed as the time shaft of the machine to which material is being fed, may be 90 an extension of said time shaft and journaled or not, as may be necessary, in the frame of the feed mechanism. C denotes the cam shaft; D a counter-shaft; E the feed roll drive shaft; F the driven feed roll shaft; 95 G a bell-crank lever for elevating the shifting feed rolls; H a rocking lever for throwing the tilting feed roll out of operative relation to the co-acting shifting feed rolls.

Upon the power shaft B is keyed a sprocket 100 wheel b driving a chain b¹ which in turn drives the counter-shaft D through the sprocket wheel d keyed thereto, which shaft may be journaled in suitable bearings I bolted or otherwise secured to the machine 105 frame. On the counter-shaft D is keyed a bevel drive gear d¹ which drives a bevel pinion d² keyed to the feed roll drive shaft

E. Upon the shaft E is slidably mounted a sleeve E¹ driven by a feather key e on the shaft E. On the upper end of the sleeve E¹ is keyed a spur gear E² on the hub of which is secured one or more feed rolls, K and K¹, which preferably consist of metal rings, each having a portion of its periphery cut away as at h and h¹, the cut away portion or gap thus formed being of greater length in one than in the other, to form unequal segments or peripheral surfaces for feeding different lengths of wire. The spur gear E² meshes with a gear E³ which is keyed to the shaft F which is journaled in a bearing provided therefor on the upper end of the lever H. The gear E³ is made with a wide face so as to remain in mesh with the gear E² when the latter gear is in either its uppermost or lowermost position.

To the shaft F at its upper end is keyed or otherwise secured a feed roll K². On the power shaft B is keyed or otherwise secured another sprocket wheel L driving a chain M which in turn drives a sprocket wheel N keyed or otherwise secured to the cam shaft C. It will thus be seen that the feed rolls K, K¹ and K² are rotated by means of the drive shaft B, the sprocket wheel b, the chain b¹, the sprocket wheel d, the bevel gears d¹ and d², the shaft E, the key e, the sleeve E¹, and the gears E² and E³, while the cam shaft C is rotated by shaft B acting through sprocket wheel L, chain M, and sprocket N. However, it is obvious that movement can be imparted to the feed roll shafts and cam shaft by other means, such as bevel or spur gearing, instead of sprocket wheels and chains, as shown, and that if the machine with which this feeding mechanism is to be used has shafts properly timed, the frame design of the feed mechanism can be changed to suit the positions of such shafts when extended, or the feed roll drive shaft E can be directly connected to one of the machine shafts, and the motion for levers G and H can be imparted by levers or other means from cams mounted on a shaft within the machine, thereby dispensing with the chains and sprocket wheel shafts B, C, and D, and bevel gears d¹ and d². The tilting feed roll K² is a plain roll having the same diameter at all points of its circumference, while the shifting rolls K and K¹ have part of their working faces or peripheries cut away, as before described, in order to adapt said rolls K and K¹ to feed different lengths, the roll K having a longer feeding face than the roll K¹, more of the feeding face of the latter being cut away, as indicated in Fig. 8, and by dotted lines at h², Fig. 8. The feed roll K² rotates at all times in one plane, and to rotate either of the co-acting feed rolls K and K¹ in the plane of roll K² the sleeve E¹ is provided with a groove at its lower end in which is fitted a divided yoke O having on opposite sides thereof studs or pintles o to fit into open-ended slots in the forked end of the bell-crank lever G, which is pivotally mounted or journaled in the machine frame and provided with a roller g near its lower end, or in position to be acted upon by the cam C¹ on the cam shaft C, so as to rock the lever G and raise the sleeve E¹, thereby raising the feed rolls K and K¹ which are lowered by the positive action of a spring P, connecting the lower end of lever G with a fixed part of the machine frame, and by gravity, to keep the roller g in contact with the cam C¹. To throw the feed rolls out of engagement for one or more revolutions, the shaft F, to which the feed roll K² is secured, is journaled in the rocking lever H, which is pivotally mounted on a stud h projecting from a fixed part of the machine frame. This lever H carries a roller h¹ near its lower end or in position to contact with a cam C² on the cam shaft C and to the lower end of the lever H is attached one end of a spring Q, the other end of which is fixed to the machine frame so that said spring will hold the feed rolls in engagement or operative relation to each other, except when disengaged by the cam C², as best shown in Fig. 5 of the drawings. At the time the blank space or gap h or h¹ on feed rolls K and K¹ is passing the small roll K², the cam C² is not in action, and to prevent the spring Q from rocking the lever carrying the roll K² so as to bring said roll K² close enough to roll K or K¹ to bend the wire or other material being fed, when more than one revolution of rolls K and K¹ is used to feed the length required, an arm R projecting from the frame is provided with an adjusting screw r by means of which the movement of the lever H may be limited so that the distance the spring Q may rock the roll K² can be adjusted or varied by adjusting said screw.

Suitable guiding means for the material being fed can be mounted upon a bracket or fixed part of the machine frame, to guide the material to the feed rolls, and also guiding means to receive the material fed can be mounted upon another bracket or fixed part of the machine frame on the opposite side of the feed rolls. When feeding the stay wire to a fence machine, it is in most cases desirable to pass the wire through a wire straightener, having two series of grooved rolls mounted in different planes, such as shown, for example, in patent to Reid, Reid and Kelley, dated November 9, 1915, No. 1,160,089, so that the wire may be drawn between the two sets of rolls and straightened, and for mounting such a straightener a shelf S may be cast with the machine frame, and when so mounted this straightener becomes one guide for guiding the wire

to the feed rolls; and a tubular guide such as shown in said Patent No. 1,160,089 may be mounted upon the fence machine and extended close up to the feed rolls, to receive 5 the wire as fed by the rolls.

The operation of my improved feeding device will be readily understood from the foregoing description when taken in connection with the accompanying drawings, and 10 is as follows. Power is applied to shaft B, which in turn, through sprocket wheel b, chain b¹, sprocket wheel d, shaft D, bevel gear wheel d¹, bevel gear pinion d², shaft E, feather e, and sleeve E¹ imparts continuous 15 motion to the feed rolls K, K¹ and K², and the same shaft B, through the sprocket wheel L, chain M, and sprocket wheel N, revolves continuously the shaft C upon which is mounted the cam C¹ which rocks 20 the bell-crank lever G, which in turn imparts upward and downward movement to the feed rolls K and K¹, and upon this same shaft is mounted the cam C² that acts upon the rocking lever H and imparts a rocking 25 movement thereto, thus tilting the feed roll K² and throwing it out of operative relation to the rolls K and K¹. Referring to 30 Fig. 3 of the drawings, just after the point Y in the revolution of the feed rolls K and K¹ has passed the line X—X, drawn through the centers of the feed roll shafts E and F, and with the lower roll K¹ in the plane of the roll K², the cam C² releases 35 the pendant arm of the lever H, whereupon the spring Q rocks said lever and moves the roll K² over to roll K¹, as shown in Fig. 1, by the time the point Y¹ of the rolls K and K¹ has nearly reached the line X—X. At 40 the time point Y¹ has reached the line X—X the wire is gripped by the feed rolls and fed a distance equal to the full-diameter circumference of the working face of feed roll K¹. If the length of wire required is greater than the circumference of the full diameter 45 or working face of the roll K¹, the rolls may be given two or more revolutions before the cam C² moves the rolls K¹ and K² out of engagement. In other words, the diameter of the rolls K and K¹ may be sufficient to 50 cause either roll to feed the required length during a portion of one revolution, or the rolls may be made smaller and given two or more revolutions to feed the required length. As soon as the required number of revolutions 55 of rolls K and K¹ has been made, and just after the point Y has passed the line X—X, the cam C² starts to separate the rolls K, K¹ from roll K², and has them fully separated just before the point Y¹ reaches 60 the line X—X. In other words, the rolls K, K¹ and K² are brought together and separated while the gap Y—Y¹ is passing the line X—X. As soon as the rolls K and K¹ have finished feeding and have been 65 separated by cam C², the cam C¹, which

meanwhile has been holding the rolls K and K¹ in an elevated position, with roll K¹ in the same plane as roll K², as shown in Fig. 1, allows rolls K and K¹ to return to their lowermost position, that is, roll K in the 70 same plane as roll K², at which time the cam C¹ releases the pendant arm of the lever H, whereupon the spring Q rocks said lever and engages the rolls K and K² while the gap in roll K is passing the line X—X, and 75 these two rolls feed in the required amount of material, the amount fed being governed by the length of feeding face on the roll K and the number of revolutions given roll K during the feeding operation. As soon as 80 the required number of revolutions for the feeding operation has been given roll K, the roll K² is thrown out of engagement therewith, while the gap in said roll is passing line X—X, at which time the cam C² elevates 85 rolls K and K¹ to throw roll K¹ in the same plane as roll K², when these two rolls are again engaged, as already explained, ready to feed a duplicate of the first length of material fed.

When desired to feed two stays simultaneously, another roll like the roll K² is mounted above the roll K², and the cam to raise and lower rolls K and K¹ is removed or the elevating parts made otherwise inoperative. When a considerable space is required between the wires fed, it will be apparent that the distance between the planes of the two sets of rolls may be made to suit the requirements by the use of distance rings 95 to separate the rolls. Also when a certain length is to be fed successively, the means for elevating rolls K and K¹ is made inoperative, and only one pair of feed rolls is used.

It will be understood, of course, that various changes may be made in the details of construction and arrangement of parts without departing from the spirit and scope of my invention; hence I do not desire to be 100 limited to the specific construction and arrangement illustrated and described. It will also be understood that while my improved feed mechanism is designed and adapted especially for use upon wire fence making 115 machines, that it is applicable to other uses, for instance, for feeding strip material to punch presses or other machinery, and in either unequal or equal lengths, simultaneously, and the invention is not restricted in 120 its application to wire fence making machines.

Having thus described my invention, what I claim as new and desire to secure by Letters Patent of the United States is: 125

1. Mechanism for feeding alternately a long and a short stay length, comprising a revoluble shaft carrying a feed roll composed of unequal segments, a single revoluble roll and means whereby it is thrown 130

alternately into and out of operative relation to one of said segments, and mechanism for throwing said segments alternately into position for coöperation with said 5 single roll in feeding a stay length.

2. In a wire fabric weaving machine, means for automatically feeding alternately a long and a short length of wire endwise across a series of strand wires into position 10 for the action of a series of loop forming and twisting devices and associated mechanisms, said means comprising a complex revoluble feed roll composed of unequal segments arranged one above another, a single 15 revoluble feed roll beside said complex roll, means for throwing said single roll alternately into and out of position for co-operative action with one of said segments, and means for shifting the position of said 20 complex roll so as to throw said segments alternately into position for coöperative action with said single roll.

3. A feeding device of the character referred to comprising a revoluble feed roll 25 composed of unequal segments arranged one above another, a revoluble roll carried by a rocking lever whereby it is thrown alternately into and out of operative relation to one of said segments, and means for throwing 30 said segments alternately into position for coöperative action with the roll carried by said rocking lever.

4. A feeding device of the character referred to comprising a plurality of superposed feed rolls slidably mounted on a shaft for imparting rotary movement thereto, a portion of the periphery of each roll being cut away so as to form unequal segments, a rocking lever carrying a feed roll in co- 40 operative relation to said first mentioned rolls, means for actuating said rocking lever so as to throw the roll carried thereby alternately into and out of operative relation to said first mentioned rolls, and means 45 for shifting the position of the latter rolls so as to bring them alternately into operative relation to the roll carried by said rocking lever.

5. Wire feeding mechanism comprising a 50 plurality of shifting feed rolls composed of unequal segments mounted one upon another on a shaft for imparting rotary movement thereto, a rocking lever carrying a feed roll adjacent and geared 55 to said shifting rolls, means for rocking said lever so as to bring the roll carried thereby alternately into peripheral alignment with one of the segments composing said shifting rolls, and means for changing 60 the position of said shifting rolls so as to bring the larger and smaller segments alternately into operative relation to the roll carried by the rocking lever.

6. A wire feeding device comprising a 65 pair of feed rolls mounted on a shaft for

imparting rotary movement thereto, each roll having a portion of its periphery cut away so as to form unequal segments, a rocking lever carrying a feed roll adjacent said pair of rolls, means for rocking said lever and throwing the roll thereon alternately into and out of operative relation to said pair of rolls, and means for shifting said pair of rolls so as to bring the larger and smaller segments alternately into operative 70 relation to the roll carried by said rocking lever. 75

7. In combination, a shaft having a sleeve slidably fitted thereon and rotatable therewith, a spur gear on said sleeve having a hub on which is secured a plurality of rings or feed rolls each having a peripheral portion cut away so as to form unequal segments, a roll mounted on a rocking lever adjacent said feed rolls; said lever carrying 80 a gear in mesh with the gear on said sleeve, means for moving said sleeve and the rolls thereon lengthwise of the shaft so as to bring the larger and smaller segments alternately into operative relation to said adjacent roll, and means for rocking said lever so as to bring the roll carried thereby alternately into operative relation with the larger and smaller segments carried by said 85 sleeve. 90

8. In a device of the character referred to, a pair of feed rolls consisting of a plurality of rings having portions of their peripheries cut away to form unequal segments, a spur gear having a hub portion on which said rings are mounted, a rocking lever, a feed roll beside said rings secured on a shaft journaled in said rocking lever and carrying a gear in mesh with the gear carrying said rings, and means for throwing 100 the roll carried by said rocking lever alternately into and out of operative relation to the other rolls, together with means for shifting the position of the latter rolls so as to bring the larger and smaller segments alternately into operative relation to the roll carried by the rocking lever. 110

9. In combination, a driven shaft having a sleeve slidably fitted thereon and rotatable therewith, a gear wheel carried by 115 said sleeve with a pair of rings secured thereon, each having a portion of its periphery cut away so as to form unequal segments constituting segmental feed rolls, a bell crank lever and means associated therewith for moving said sleeve lengthwise of the shaft to shift the position of said feed rolls, a rocking lever having a shaft journaled therein carrying a feed roll adjacent 120 said segmental rolls, and means for rocking 125 said lever so as to throw the roll carried thereby alternately into operative and inoperative relation to the segmental feed rolls.

10. A wire feeding device comprising a 130

plurality of feed rolls composed of unequal segments mounted on a shaft for imparting rotary movement thereto, means for raising and lowering said rolls, a roll beside 5 said segmental rolls arranged to rotate in coöperative relation thereto, and means for rotating the latter roll and throwing it alternately into and out of operative relation to that one of said segmental rolls which 10 at the time may be arranged in the same plane.

11. A stay wire feeding device for wire fence machines adapted to project the wire from a coil endwise across a series of strand 15 wires into position for the action of a series of stay attaching devices, said feeding devices comprising a plurality of feed rolls composed of unequal segments mounted on a shaft for imparting rotary movement 20 thereto, means for raising and lowering said rolls, a roll beside said segmental rolls arranged to rotate in coöperative relation thereto, and means for rotating the latter roll and throwing it alternately into and 25 out of operative relation to that one of said segmental rolls which at the time may be arranged in the same plane.

12. A feeding device of the character referred to comprising a plurality of feed 30 rolls arranged one upon another and having unequal feeding surfaces, means for rotating said rolls in unison, a co-acting feed roll and means for rotating it, together with means for bringing said co-acting roll 35 alternately into operative relation with one of said feeding surfaces for feeding alternately material in different lengths.

13. A feeding device of the character referred to comprising a plurality of feed 40 rolls consisting of unequal segments mounted one upon the other, means for rotating said segments in unison, a co-acting feed roll beside said segments, and geared thereto, together with means for bringing the 45 latter roll alternately into operative relation with the larger and smaller segments for feeding alternately material in different lengths.

14. A feeding device of the character referred to comprising a single roller element 50 rotatably mounted on a rocking support, a plurality of sidewise movable roller ele-

ments rotatably mounted beside said single element, and means for rotating said elements, together with means for rocking 55 said support and moving said plurality of elements so as to bring the peripheral surfaces thereof alternately into coöperative relation to said single roller element, for feeding material in desired lengths. 60

15. A feeding device of the character referred to comprising a driven shaft carrying a plurality of sidewise movable roller elements, a roller element rotatably and rockingly mounted beside said plurality of 65 elements, means for rotating said elements, and means for moving said plurality of elements and throwing said single element alternately into operative relation with one and then another of said plurality of elements, for feeding material in desired 70 lengths.

16. Mechanism for feeding wire or other flexible material longitudinally or endwise alternately in comparatively long and short 75 lengths, comprising a pair of revoluble feed rolls composed of unequal segments, co-acting rolling means adjacent said segments, means for revolving said segments and rolling means, and means for causing said rolling means to coöperate alternately with said segments so as to feed the material in the desired lengths. 80

17. A feed mechanism constructed and adapted to intermittently move a wire or 85 other material longitudinally a predetermined length, comprising a pair of unequal segmental feed rolls, rolling means arranged to coöperate with said segmental rolls alternately in feeding the required lengths, 90 and means for revolving said segmental rolls and rolling means, together with means for bringing first one segmental roll and then another into coöperative relation to said rolling means so as to feed the material 95 alternately in comparatively long and short lengths.

In testimony whereof I affix my signature in the presence of two witnesses.

WALTER V. REID.
